UNITED STATES PATENT OFFICE.

HARRY L. WHITNEY AND ROSS E. WYANT, OF TOLEDO, OHIO.

BEEHIVE INSPECTION AND ELEVATING APPARATUS.

Application filed December 20, 1926. Serial No. 156,025.

This invention relates to apparatus for use in bee culture operations, and is particularly designed for use by beekeepers in the manipulation of bee hives at such times as it becomes necessary to inspect the hives, for the purpose of examining the broods, or for removing full supers or bee hive sections and replacing these with empty sections.

10 Accordingly, we have devised an improved form of apparatus adapted for convenient application to a bee hive, and readily to clamp and elevate any desired number or group of the supers or sections of the hive, 15 and permit inspection and removal of the desired unit or section without disturbing any of the remaining sections of the hive.

As one form of construction for embodying these improvements, we have devised a 20 framework having clamping means for quickly and conveniently engaging one of the lower sections of the hive, and also including a movable frame likewise including clamping means for engagement with one of 25 the upper sections of the hive, together with efficient means for quickly elevating the movable frame and thereby separating the upper bee hive sections from the lower sections to which the main frame has been clamped.

30 Further objects and advantages of the invention will become apparent as the disclosure proceeds and the description is read in connection with the accompanying drawings illustrating a selected embodiment of the invention.

With these general objects in view, therefore, the invention will now be described by reference to the accompanying drawings, after which those features and combinations 40 deemed to be novel will be particularly set forth and claimed.

In the drawings—

Figure 1 is a side elevation, illustrating a bee hive inspection and elevating apparatus 45 constructed in accordance with the present invention;

Figure 2 is a rear elevation of the same, but with the bee hive clamping means represented as having been operated to clamp the 50 selected sections of the hive;

Figure 3 is an irregular horizontal sectional view, illustrating both sets of the clamping devices in clamping engagement with the bee hive;

55 Figures 4 and 5 are sectional detail views,

representing sections taken on the lines IV—IV and V—V, respectively, of Figure 3; and

Figure 6 is a detail view, with broken lines, representing different operative positions of one of the eccentric means for actuating the clamping devices.

Referring now to the said drawings in detail, these illustrates the improved apparatus as comprising what may be termed a 65 main frame made up of any suitable material, such as angle iron framework, and including a lower or base frame portion 10 which is substantially of U-shape, as shown in Figure 3, so as to adapted the same to 70 be applied to the rear of a hive and permit the sides of the frame to pass over or across the sides of the bee hive sections or supers 12, as required for the later steps of the operation. Preferably, the framework is 75 made ample in size in order to provide plenty of room between it and the hive, thereby facilitating the work of inspecting the hive both from the front and rear, and thus also facilitating any operations necessary in the removal and replacement of 80 supers.

At the rear of the lower or base frame portion 10 are provided the upright frame members 14 equal in height to the maximum height of hives with which the apparatus may be used, the upper portions of said members 14 extending forwardly, as shown in Figure 1, and having their forward ends secured to upright guide rods 15, the lower 90 end portions of which are secured to the lower or base frame portion 10.

Upon the vertical guide rods 15 are mounted a pair of vertically sliding sleeves 16 which serve to support the movable super 95 clamping frame which comprises a U-shaped frame member 17 having the angularly arranged brace or stay rods 18 connecting said frame 17 with the upper portions of the sleeves 16 (see Figure 1). The upper ends of said sleeves 16 are also provided with collars 20 for the attachment of lifting cables 22 operating around pulleys or sheaves 23 journaled in brackets 24 at the upper ends of the frame members 14. The cables 22 are operatively connected with a winding shaft 25 mounted in brackets 26 carried by the frame members 14, said shaft having square ends projecting at either side of the framework for the application of a suitable 105 110

crank 27 in winding up the cables 22, and thereby elevating the frame 17 to the desired height. One end portion of the shaft 25 is fitted with a ratchet element 28 engaged by a suitable pawl 29 in such a manner as to hold the shaft 25 against reverse rotation, and hence retain the movable frame 17 elevated, until said pawl 29 is disengaged from the ratchet 28, for unwinding of the cables 22.

At the front corners of the lower or base portions 10 of the main framework are provided clamping devices comprising movable clamp members 32 swinging on vertical pivot pins 33 and actuated by springs 34 (Figure 4) into normally open position, as illustrated in Figure 1. These clamp devices are so arranged as to be swung, by means of cables 35 into engagement with the front corners 20 of a super or hive section 12, as shown in Figure 3, the clamp members being preferably lined with suitable friction material 36, adapted to securely engage the face of the super, without slipping, and at the same time prevent marring or scratching the surface of the hive. The cables 35 are attached to the clamp members by means of eyebolts 37 engaging leaf springs 38 carried by the clamp members and designed to maintain the cables 35 always in a taut condition, and at the same time permit the cable lengths to be adjusted as required. These cables are carried round pulleys or sheaves 40 at the corners of the frame work 10, and thence they 30 are carried and attached to suitable sheave segments 42 secured to the opposite ends of a rocker shaft 43 journaled in hanger brackets 44 carried by the upper portions of the frame members 14, adjacent to the shaft 25. The intermediate portion of the shaft 43 is provided with a suitable operating handle 45 shown in lowered or clamp releasing position in Figure 1, and in raised or clamp applying position in Figure 2. The center 40 of the sheave segments 42 is so arranged with reference to the center of the rocker shaft 43 that in the operation of the handle 45 the cables 35 are swung past center (of said shaft 43) in the operation of the handle 45 to the raised position shown in Figure 2, thus in effect locking all the parts with the clamp members 32 in the position illustrated in Figure 3.

The front corners of the movable frame 17 are likewise provided with clamp members 32' similarly mounted to swing upon pivot pins 33' into either the open position shown in Figure 1 or the closed position shown in Figures 3 and 4, and operated into the latter position by means of cables 35' connected to the clamp members 32' by means of bolts 37' and leaf springs 38'. The other ends of these cables 35' are attached to similar sheave segments 42' carried by the opposite ends 50 of a rocker shaft 43' mounted in bearings 44'

carried by the rear of said movable frame 17. The sheave segments 42' are actuated about the axis of the shaft 43' by means of either of a pair of handle members 48 connected with said sheave segments, the arrangement being such that in the movement of said handles 48 from lowered position, corresponding to the open position of the clamp members 32', into upright position as shown in Figures 2 and 3, corresponding to the closed position of said clamp members, the cables 35' are swung across or past center (of said shaft 43'), as represented by the broken lines in Figure 6, thus in effect locking the parts in this relation, and holding the clamp members 32' in engagement with the corners of the selected super or hive section 12.

Preferably, the lower clamp operating cables 35 are arranged to swing into engagement with a pair of safety catch elements 50 mounted in brackets 52 carried by the lower or base portion 10 of the frame, (see Figure 5) each of said elements 50 being provided with a spring element 53 operating to maintain the catch element 50 normally in outward or inoperative position. The arrangement is such that as the lower cables 35 swing inward toward the hive, in response to the inward swinging movement of the corresponding clamp members 32, said cables engage and actuate the catch elements 50 into engagement with the sides (or ends) of the super or hive section 12, the purpose being to engage the free ends of the elements 50 with the hand holes 54 with which the supers are commonly provided.

Similarly, the cables 35' for operating the upper clamp members 32' are designed to engage similar safety catch devices 50' pivotally carried by brackets 52' provided on the inside of the movable frame 17 (see Figure 5). The catch members 50' are presented in upwardly projecting relation (in contrast to the downwardly projecting catch members 50) whereby, on inward movement of the upper cables 35' in response to the inwardly swinging movement of the clamp members 32', the catch members 50' are engaged and actuated into position to be carried into the hand holes 54 of the corresponding super, as illustrated in Figure 5. As with the catch members 50, the catch members 50' are also actuated normally into inoperative position by means of spring elements 53'. Obviously, the action of the lower catch devices 50 is to prevent the apparatus from slipping below a certain point upon the lower super or bee hive section, whereas the other safety catch elements 50' have the opposite action of preventing or limiting the slipping of the movable frame 17 and its parts in an upward direction after engagement of the clamp members 32' with the selected super.

The inside of the framework 10, as well

as of the movable frame 17, at those points where they are brought into engagement with the hive sections 12 are also lined with the friction material 36, similar to that with 5 which the clamp members 32 and 32' are lined, and for the same purpose.

For facilitating the centering of the framework with reference to the hive, in applying the apparatus into operative position, the 10 guide brackets 60 are provided at the inside of the lower or base portion 10, as shown in Figure 3. A padded bracket 62 is provided at the rear of the base portion 10 for engagement by the knee of the operator, to assist in 15 manipulating the apparatus.

In the operation of the apparatus, the bee-keeper lifts and carries the appliance by means of the shaft 25, and after presenting the open side of the framework opposite the 20 hive, and with the clamping devices swung into outward or open position as shown in Figure 1, the framework is moved into position embracing the rear and sides (or ends) of the hive, as illustrated in Figure 3, this 25 operation being facilitated by pressing with the knee upon the knee bracket 62, and the guides 60 serving to center the framework about the hive. Now after the framework has been elevated sufficiently for the purpose 30 of bringing the lower clamping devices 32 opposite to the super or hive section 12 which is selected as the lowermost section to be left undisturbed while the remaining upper supers are to be raised therefrom, the handle 35 45 is swung upward for actuating said devices 32 into firmly clamped engagement with the corners of the super. Now the operator can release his hold on the shaft 25 and, by simply operating one of the handles 40 48, actuates the corresponding clamping devices 32' into clamping engagement with one of the hive sections 12 or supers above that clamped by the devices 32. As already explained, these clamping means are automatically 45 locked and held securely after operation of the corresponding handles 45 and 48, and remain locked until released by the reverse operation of the handles. The crank 27 may now be rotated for raising the frame 17 and the super 12 engaged therewith to any 50 desired elevation necessary for inspecting the separated supers or hive sections, and making any replacements that may be required, during which operation the pawl 29 retains the parts in elevated position without any further attention on the part of the operator. By releasing the clamping devices 32' and further elevating the frame 17 and reclamping said devices, any super 12 55 may be selected and elevated as required for completing the inspection and attention necessary for the particular hive in question.

It will thus be noted that by our improved apparatus the labor incident to such 60 inspecting and elevating and replacement

operation is reduced to a minimum, and likewise the necessity of tearing down a hive is eliminated, and likewise the loss which has heretofore been incurred both in honey and in bees, due to excessive agitation involved in 70 the tearing down and rebuilding of the hives.

It will also be noted that the frame members 14 project forwardly sufficiently to bring the lifting cables 22 in the vertical plane passing through the centers of the hive sections, and to guard against any tendency to tip or rock the guide rods 15 and sheaves 16 are provided and hence any swinging tendency of the suspended portion of the hive is effectively prevented. While we have illustrated what we now regard as the preferred form of construction for embodying the proposed improvements, we expressly reserve the right to make all such changes or modifications as may fairly fall within the scope 80 of the appended claims.

What we claim is:

1. Elevating apparatus for bee hives, comprising a main frame, means for rigidly clamping said frame to one of the lower hive sections, a vertically movable frame slidably connected with said main frame and having means for clamping said movable frame to one of the upper hive sections, and means for raising and lowering said movable frame. 90

2. Elevating apparatus for bee hives, comprising a main frame of U-shape in horizontal section, clamping means operable from the rear of said frame for clamping the same to the corners of one of the lower hive sections, a vertically movable frame slidably connected with said main frame and having clamping means operable from the rear of the apparatus for clamping said movable frame to the corners of one of the upper hive sections, and means also operable from the rear of the apparatus for raising and lowering said movable frame. 100

3. Elevating apparatus for bee hives, comprising a main frame, means for rigidly clamping said frame to one of the lower hive sections, a movable frame having means for clamping the same to one of the upper hive sections, vertical guide means connecting said frames, and means for raising and lowering the said movable frame. 110

4. Elevating apparatus for bee hives, comprising a main frame of U-shape in horizontal section, means for rigidly clamping said frame to one of the lower hive sections, a movable U-shaped frame having means for clamping the same to one of the upper hive sections, means forming vertical guideways for said movable frame at opposite sides of the main frame, and means for raising and lowering said movable frame. 120

5. Elevating apparatus for bee hives, comprising a main frame, a vertically movable frame slidably connected to said main frame, pivoted clamping devices carried by 130

each of said frames and movable into clamping engagement with the corners of the hive sections, means for operating said clamping devices from the rear of the apparatus, and means for raising and lowering said movable frame.

6. Elevating apparatus for bee hives, comprising a main frame, a vertically movable frame slidably connected to said main frame, pivoted clamping devices carried by each of said frames and movable into clamping engagement with the corners of the hive sections, means comprising cable connections from the rear of the apparatus for independently operating said clamping devices, and means for raising and lowering said movable frame.

7. Elevating apparatus for bee hives, comprising a main frame, a vertically movable frame slidably connected to said main frame, pivoted clamping devices carried by each of said frames and movable into clamping engagement with the corners of the hive sections, means for independently operating said clamping devices from the rear of the apparatus comprising cables provided with yielding take-up elements connected with said devices, and means for raising and lowering said movable frame.

8. Elevating apparatus for bee hives, comprising a main frame, a vertically movable frame slidably connected to said main frame, pivoted clamping devices carried by each of said frames and movable into clamping engagement with the corners of the hive sections, means comprising cable connections from the rear of the apparatus for independently operating said clamping devices, and including eccentric sheave segments movable to swing the cables through center into clamp-locking position, and means for raising and lowering said movable frame.

9. Elevating apparatus for bee hives, comprising a main frame, means for rigidly clamping said frame to one of the lower hive sections, a movable frame having means for clamping the same to one of the upper hive sections, means for raising and lowering said movable frame, and safety catch elements carried by said main frame and adapted to engage said lower hive section.

10. Elevating apparatus for bee hives, comprising a main frame, means for rigidly clamping said frame to one of the lower hive sections, a movable frame having means

for clamping the same to one of the upper hive sections, means for raising and lowering said movable frame, and safety catch elements carried by said movable frame and adapted for engagement with said upper 60 hive section.

11. Elevating apparatus for bee hives, comprising a main frame, means for rigidly clamping said frame to one of the lower hive sections, a movable frame having means 65 for clamping the same to one of the upper hive sections, means for raising and lowering said movable frame, and oppositely acting safety catch elements carried by said frames and adapted for respective engagement with said upper and lower hive sections.

12. Elevating apparatus for bee hives, comprising a main frame, a vertically movable frame slidably connected to said main frame, clamping devices carried by said main frame and movable into clamping engagement with the corners of one of the hive sections, means for operating said clamping devices into clamped position, and safety 80 catch elements carried by said main frame and adapted to be actuated by said clamp operating means into engagement with the sides of the hive section.

13. Elevating apparatus for bee hives, 85 comprising a main frame, a vertically movable frame slidably connected to said main frame, clamping devices carried by said movable frame and movable into clamping engagement with the corners of one of the hive sections, means for operating said clamping devices from the rear of the apparatus, and safety catch elements carried by said movable frame and adapted to be actuated by said clamp operating means into engagement 90 with the sides of the hive section.

14. In an apparatus of the character described, a frame provided with clamping devices adapted for engagement with the corners of a bee hive section, cables operatively connected with said clamping devices, and safety spring-actuated catch elements adapted to be engaged and operated by said cables into engagement with the sides of the 100 hive section.

In witness whereof we hereunto affix our signatures.

HARRY L. WHITNEY.
ROSS E. WYANT.
